UNITED STATES PATENT OFFICE.

ARTHUR J. WEST, OF PITTSBURG, PENNSYLVANIA, ASSIGNOR TO THE WESTINGHOUSE MACHINE COMPANY, A CORPORATION OF PENNSYLVANIA.

GAS-ENGINE MIXING-VALVE.

No. 876,509.

Specification of Letters Patent.

Patented Jan. 14, 1908.

Application filed September 1, 1904. Serial No. 222,969.

To all whom it may concern:

Be it known that I, ARTHUR J. WEST, a citizen of the United States, and a resident of Pittsburg, in the county of Allegheny and State of Pennsylvania, have invented a new and useful Improvement in Gas-Engine Mixing-Valves, of which the following is a specification.

This invention relates to internal combustion engines and more particularly to gas engines and means for controlling the supply of air and gas thereto.

The means now employed (with which I am familiar) for controlling the air and gas supplies to engines, and more especially to large engines (I refer particularly to engines such as those which have been built within the last few years for utilization with blast furnace and producer gases) are more or less costly and for the duties which they are called upon to perform, complicated and delicate.

When the governing of such engines is accomplished by the so-called gas throttling method it is essential, when using a lean or poor gas, to increase the relative amount of air admitted as the gas supply is throttled, and vice versa, to insure as nearly as possible the admission of a constant volume, and therefore the maintenance of as nearly as possible a constant compression.

To produce simple, relatively cheap and efficient means for regulating the supply of air and gas to gas engines, and varying the relative proportions of air and gas admitted has been an object of this invention.

A further object has been to produce relatively simple means whereby the relative proportions of air and gas admitted are automatically changed either according to the load demands or the changes in the speed of the engine.

A still further object has been to produce means, which, in addition to having the capabilities as above outlined is so constructed that the normal relative proportions of air and gas admitted may be varied or adjusted to suit the gas used.

These as well as other objects I attain in the means described in this specification and illustrated in the drawings presented herewith throughout which corresponding elements are denoted by like characters.

The engine, the governor and the mechanism controlled by the governor for actuating

the governor rod (hereinafter referred to) and the mechanism for reciprocating the admission valve have been omitted from the drawings, as they form no part of this particular invention, and further, as their construction and details may be varied to suit the many conditions encountered.

In the drawings Figure 1 is a sectional elevation of a device embodying this invention, and Fig. 2 illustrates in perspective several of the elements entering into the make-up of the means for actuating the air and gas valves hereinafter referred to.

The device consists of a valve casing 3 bolted or otherwise secured to the engine cylinder and provided with a valve seat for a reciprocable puppet valve 4, preferably of the mushroom type. Axially in line with stem 5 of said valve and included within casing 3, is a casing 6 having a bore 7 provided with gas ports 8 and a gas inlet passage 9.

Valve casing 3 is provided with an air passage 10, and a valve 11 preferably of the balanced butterfly type is mounted within said air passage and provided with a rotatable stem 12 extending up through the top of casing 3.

A piston valve 13 provided with ports 14 of the same shape, number and size as ports 8 is carried by stem 5 of the admission valve within bore 7 of casing 6, and a displacer head 15 is formed integral with the piston valve whereby, as said valve is depressed, said head will displace the gas and air which lie below it.

If desired the piston valve may be formed so as to rotate relative to the admission valve to vary the effective area of the gas ports, but this is not necessary as the piston valve when rotated to vary the effective area of said ports may carry with it the admission valve.

A reciprocable governor rod 16 controlled by the engine governor and mounted in any suitable manner is connected to the piston valve by means of a link 17 and an arm 18 connected to said piston valve stem. From this construction it will be seen that as the governor rod is reciprocated the piston valve will be rotated, and thereby the effective area of the gas ports varied when the ports formed in the piston valve are opposite the ports 8 of the valve casing bore during the reciprocations of the piston and admission valves.

Link 17, each end of which carries a ball mounted in a coöperating socket, as shown in Fig. 2, is of sufficient length so that the oscillations of the piston valve during its reciprocations due to the fixed length of link 17 will be negligible and will not materially affect the effective area of the gas ports.

By means of a link connection, similar to 17, governor rod 16 is connected to an oscillating bifurcated member 19 which is mounted on a reduced portion 20 of the valve casing concentric with valve stem 12. Rigidly secured to valve stem 12 is a valve lever 21 provided with a plurality of openings 22 adapted to carry a pin 23 which projects therethrough and lies between the furcate parts of member 19. Surrounding reduced portion 20, adjustable thereon and rigidly secured in its adjusted position is a member 24 carrying two springs 25 which embrace a downwardly projecting portion 26 of valve lever 21 (it will be understood that in the drawings valve lever 21 is shown in an inverted position for the sake of illustration 25 and when in operative position will stand so that pin 23 projects downwardly between the furcate parts of member 19 and tend to yieldingly hold the valve in its normal position).

It will be seen that by rotating member 24 the normal position of the butterfly valve 11 may be changed and it will further be seen that as member 19 is oscillated the butterfly valve may be oscillated to either increase or decrease the effective area through the valve according to the position of pin 23; that is, according to which of the holes 22, pin 23 projects through.

It will be seen that by means of this lost motion mechanism between the governor rod 40 and valve 11 the relative proportions of the air and gas admitted may be varied as desired.

It will be understood that any means for 45 accomplishing a variation in the relative movements of the gas and air valves may be utilized and a lost motion connection is not necessary but in some cases may be desirable.

Many changes may be made in the forms 50 and arrangement of the several elements comprised in the make-up of the means illustrated without departing from my invention, since.

I claim:

1. In combination in a gas engine, an admission valve, a rotatable reciprocably mounted gas valve, an air valve, a variably reciprocable member dependent upon the engine speed for controlling said air and gas valves and a regulable lost motion connection between said air valve and said member.

2. In combination in a gas engine, a reciprocable admission valve, a gas valve, an air valve, a movable member dependent upon

the engine speed for regulating said air valve, a lost motion connection between said member and said air valve, and means for varying the amount of said lost motion.

3. In combination in a gas engine, a reciprocable admission valve, a gas throttling piston-valve movable with said admission valve and rotatable to vary the gas supply, an air valve and means operable during the reciprocations of said admission valve and dependent upon the engine speed for controlling said gas and air valves to vary the gas and air supplies.

4. In combination in a gas engine, a reciprocable admission valve, a gas throttling piston-valve movable with said admission valve and rotatable to vary the gas supply, an air valve, means operable during the reciprocations of said admission valve and dependent upon the engine speed for controlling said gas and air valves to vary the gas and air supplies and instrumentalities for varying the relative proportions of air and gas admitted.

5. In combination in a gas engine, a mixture admission valve, a ported valve casing axially in line therewith, a rotatable piston-valve carried by the admission valve stem within said casing and provided with ports at times adapted to register with the ports of 90 said casing, an air supply, a displacer head carried by said admission valve stem within said casing, means for varying the relative proportions of air and gas passing said admission valve, and instrumentalities for rotating said piston valve to vary the effective area of said ports coincident with the speed variations.

6. In combination in a gas engine, an admission valve, a rotatable reciprocably mounted gas valve, an air valve, a variably reciprocable member dependent upon the engine speed for regulating said air and gas valves and a regulable connection between said air valve and said member.

7. In combination in a gas engine, a reciprocable admission valve, a gas valve, an air valve, a movable member dependent upon the engine speed for regulating said air valve, a lost motion connection between said member and said air valve, means for varying the amount of said lost motion and agents tending to yieldingly hold said air valve in normal position.

8. In combination in a gas engine, a mixture admission valve, a gas valve, an air valve, a variable reciprocating member dependent upon the speed of the engine for controlling said gas and air valves, and a device comprising two springs between said air valve and said member for returning said air valve to its normal position.

9. In combination in a gas engine, a mixture admission valve, a ported valve casing axially in line therewith, a rotatable piston

- valve carried by the valve stem for said admission valve and provided with ports adapted to coöperate with the ports of said casing to control the passage of fluid therethrough, 5 an air supply, a displacer head carried by said piston valve stem within said casing, and means, dependent upon the speed of the engine, for rotating said piston valve to vary the effective area through the ports of said 10 casing.
10. In combination in a gas engine, a reciprocable mixture admission valve, a gas throttling piston valve movable with said admission valve, an air valve, and means, dependent upon the speed of the engine, for rotating said piston valve and said air valve. 15
11. In combination in a gas engine, a reciprocable mixture admission valve, a gas throttling piston valve movable with said 20 admission valve, an air valve, means dependent upon the speed of the engine for operating said piston valve and said air valve to control the supply of air and gas, and means for independently adjusting said air valve.
- 25 12. In combination in a gas engine, a reciprocable mixture admission valve, a gas valve, an air valve, a movable member which depends upon the speed of the engine for its position and which controls said air and said 30 gas valves, a lost motion connection between said member and said air valve, and means for yieldingly holding said air valve to its normal adjustment.
- 35 13. In combination in a gas engine, a reciprocable mixture admission valve, an air valve, a movable member which depends upon the speed of the engine for its position and which regulates said air valve, and a regulable connection comprising two springs 40 between said member and said air valve.
- 40 14. In combination in a gas engine, a reciprocable mixture admission valve, a rotatable gas valve carried by the admission valve, an air valve, and means, dependent upon the speed of the engine, for varying the relative proportions of air and gas passing through said admission valve. 45
15. In combination in a gas engine, a mixture admission valve, a rotatable gas valve carried by said admission valve, an air valve, means, dependent upon the speed of the engine, for varying the position of said gas valve and said air valve, and an adjustable lost motion connection between said means and said air valve for varying the relative proportion 50 of air and gas passing said admission valve. 55
16. In combination in a gas engine, a mixture admission valve, a gas valve, an air valve, and means, dependent upon the speed of the engine, for varying the position of said gas and said air valves, and comprising a lost motion connection for said air valve, embodying a spring restrained lever rigidly connected to said air valve. 60
17. In combination in a gas engine, a mixture admission valve, a gas valve, an air valve, and means, dependent upon the speed of the engine, for varying the position of said air and said gas valves, comprising a lost motion connection for said air valve, embodying a spring restrained lever rigidly connected to said air valve, a movable contact pin, and a member for contacting with said pin, actuated by said means. 65
- In testimony whereof, I have hereunto subscribed my name this 31st day of August, 1904. 70

ARTHUR J. WEST.
